UNITED STATES PATENT OFFICE.

ELMER E. PRICE, OF CHICAGO, ILLINOIS, ASSIGNOR TO EUGENE DIETZGEN COMPANY, OF CHICAGO, ILLINOIS, A CORPORATION OF DELAWARE.

BOOK.

Application filed March 12, 1927. Serial No. 174,793.

My invention relates to books, especially catalogs and the like, and one object of the invention is to provide a book so constructed that the ordinary run of goods may be described on the main leaves of the book and a special display of specific items may be described in a separate and conspicuous place, but enclosed under an individual cover and also under the main cover. Another object 10 is to provide in a construction of this character the option of omitting the second line of goods in some of the catalogs without disturbing the body thereof, thus affording the manufacturer the choice, without changing 15 his catalog, of either including or excluding a listing of the special class of goods.

A further object is to provide a construction such that the inner or supplementary book may be automatically closed when the 20 front cover of the main book is closed. Still another object is to so arrange the structure that the title page of the supplemental book may be exposed to view when the cover page of the main book is hidden; as is the case when 25 the main book is open.

I accomplish these objects by the construction shown in the accompanying drawings, in which

Figure 1 is a perspective view of the complete article, showing the front cover of the main book open and the back cover of the supplemental book also open.

Figure 2 is an end view of the book looking upward from the bottom thereof.

Figure 3 is similar to Figure 2, but showing the back cover of the supplemental book closed.

Like numerals denote like parts throughout the several views.

According to the illustrated construction the main book has a body of leaves 10, a back cover 12, and a front cover 14. These are of ordinary construction.

The supplemental book has a body of leaves 16, a front cover 18, and a back cover 20. By preference the supplemental book is smaller than the main one and the cover hinge 22 is spaced at a distance from but parallel to the point 24 at which the front cover of the main book is hinged.

The front cover of the supplemental book is pasted or otherwise secured to the inside of the front cover of the main book. The result is that to open the inner book it is necessary first to swing the main front cover 14 to

the left and then swing the rear cover 20 to the right, as illustrated in Figure 1. It is desirable to apply printing to the outside of the rear cover of the supplemental book as indicated at 26 in Figure 3.

The leaves 16 of the supplemental book are fastened at the top to the front cover 18 by staples 28 or other appropriate means, and in the illustrated construction the leaves are graduated in length, the shortest being at the top, although this is a detail which may be varied. Thus to examine the contents of the inner book the leaves are raised. This arrangement avoids the unusual and awkward condition that arises in turning the leaves of the inner book backward to expose them one by one.

When the book is closed the user first swings back the main front cover 14, whereupon the outer surface of the rear cover 20 of the supplemental book will be exposed, thus advising the user of the contents of the inner book. The user then swings the rear cover 20 in the opposite direction, that is, toward the right, as shown in Figure 1, thus exhibiting the uppermost surfaces of the leaves 16. To examine this inner book the leaves may be raised and swung about the hinge formed at the fastening devices 28. The leaves of the inner book are hinged along a line parallel to the top of the book and at right angles to the hinges 22 and 24.

When the user is through with the book all he has to do is to swing the main cover 14 to closed position, whereupon the rear cover of the inner book will be automatically closed by contact with the leaves 10 of the main book. Thus it is unnecessary to take any precaution to see that the inner book is closed before closing the outer. This fact has great importance for in books where there are maps or other inserts it is necessary to carefully close the insert before closing the book in order to prevent crushing of the leaves.

From the foregoing it will be evident that my device constitutes a unitary structure including a left-hand and a right-hand opening book, one within the other, and that the inner book which opens in an opposite direction from the normal book has its leaves bound at the top which causes the upper page of the inner book to be exposed immediately the front cover of the inner book is raised. All portions of the inner book except the rear cover thereof are secured to the front cover

of the main book, and the front leaf of the inner book is immediately exposed upon raising the front cover of the inner book, which constitutes a novel and highly convenient and practical construction.

Having thus described my invention what I claim as new and desire to secure by Letters Patent is:

1. A compound book having a main body of leaves and a front and back cover, supplemental leaves fastened to the inside of the main front cover, and a supplemental cover for the supplemental leaves hinged adjacent the inner edge of the main front cover and at the right edge of the front supplemental leaves along a line parallel and adjacent to the hinge of the main front cover, thereby positioning the rear cover of the inner book so as to be properly closed by the engagement therewith of the leaves of the main body in response to the closing of the main body of leaves.
2. A compound book having a main body of leaves and a front and back cover, supplemental leaves fastened at their upper edges to the inside of the main front cover, and a supplemental cover for the supplemental leaves hinged to the inside of the main front cover at the right edge of the supplemental leaves and along a line parallel and adjacent to the hinge of the main front cover, thereby positioning the supplemental cover so as to insure the closing of said supplemental cover upon the engagement therewith of the main body of leaves in response to the closing of the book including said main body of leaves.
3. A compound book having a main body of

leaves and a front and back cover, a supplemental book having a front and back cover, and supplemental leaves, the front cover of the supplemental book being secured to the inside of the main front cover, and the rear cover of the supplemental book being hinged at the right edge of the supplemental leaves whereby the upper leaf of the supplemental book may be exposed by opening the main cover to the left and the back cover of the supplemental book to the right, said supplemental cover being so positioned as to be positively closed in response to the engagement therewith of the main body of leaves when said compound book is closed.

4. A compound book having a main body of leaves and a front and back cover, a supplemental book having a front and back cover, and supplemental leaves fastened to the upper edge of the front cover of the supplemental book, said front cover of the supplemental book being fastened to the inside of the main front cover, and the back cover of the supplemental book being hinged at the right edge of the supplemental leaves whereby the upper leaf of the supplemental book may be exposed by opening the front cover of the main book to the left and the back cover of the supplemental book to the right, and whereby the back cover of the supplemental book will be closed in response to the engagement therewith of the main body of leaves when the compound book is closed.

In witness whereof, I have hereunto subscribed my name.

ELMER E. PRICE.
